UNITED STATES PATENT OFFICE.

LAWRENCE R. BLACKMORE, OF NEWARK, NEW JERSEY.

DESIGN FOR A RADIATOR.

SPECIFICATION forming part of Design No. 22,401, dated May 2, 1893.

Application filed March 9, 1893. Serial No. 465,353. Term of patent 7 years.

To all whom it may concern:

Be it known that I, LAWRENCE R. BLACKMORE, a citizen of the United States, residing at Newark, Essex county, New Jersey, have 5 invented a certain new and original Design for Radiators, fully described and represented in the following specification and the accompanying drawings, forming a part of the same.

The annexed drawings illustrate a radiator 10 embodying my design; Figure 1 being a side elevation, and Figs. 2 and 3 sectional plans on lines *x*, *x*, and *y*, *y*, respectively, in Fig. 1.

The radiator exhibits an appearance of two 15 columns *a*, *a'*, joined at their ends by loops *b* and crossed intermediate to such ends. Such crossing imparts to the radiator an appearance of two pairs of columns one above the other, each column in the upper pair extending beyond the crossing into the opposite side 20 of the pair below. The columns are shown

of flattened oval form and the crossing *c* resembles in appearance the so-called "cross" used in pipe fittings. Each column is curved inwardly at the crossing, the contour of the radiator thus resembling a figure "8."

The essential feature of my design is embodied in a radiator formed with two vertical columns united at the top and bottom and crossed intermediate to their ends.

Having thus set forth the design, what I 30 claim herein is—

The design for a radiator, substantially as herein shown and described.

In testimony whereof I have hereunto set my hand in the presence of two subscribing 35 witnesses.

LAWRENCE R. BLACKMORE.

Witnesses:

G. C. BLACKMORE,
THOMAS S. CRANE.
